UNITED STATES PATENT OFFICE

HARRY BONAT, OF NEW YORK, N. Y.

HAIR-PERMANENT-WAVING HEATER

Application filed July 26, 1928. Serial No. 295,430.

This invention relates to heaters and more particularly to heaters for use in connection with hair permanent waving.

An object of the invention is to provide 5 a new, simple and efficient heater for use in connection with hair permanent waving.

Heretofore in the art of hair permanent waving use has been made of heaters composed of sections hinged together in such a 10 manner and of such shape as to form a clamp. A heater of such clamp-like arrangement when in use fitted very closely against the roll of hair to be treated and applied pressure thereto. The application of heat under

15 pressure to the hair often resulted in damage thereto and furthermore due to the construction of the clamp-like heater a large part of the vapor resulting from the heating process was freely dissipated. Due to this 20 rapid dissipation of vapor the heat would necessarily have to be applied for a considerable length of time, often times resulting in damage to the hair and moreover affording greater discomfort to the patient.

25 Accordingly the present invention overcomes the unsatisfactory features of the devices in use heretofore by providing a unitary structure of a size and shape to fit closely around the roll of hair to be treated without actually applying any pressure thereto. Due to the unitary structure the vapors are 30 held in close contact with the roll of hair under treatment with the result that the time necessary for treatment is considerably reduced and the operation is made more efficient.

35 Moreover the use of a unitary structure which is affixed to the spool around which the hair under treatment is rolled, by means of heat insulating clamps lessens the liability 40 of the scalp of the patient being burned due to heat conducting materials. The improved structure is easier to handle than existing devices and produces better results. The 45 clamps themselves serve to close the end of the unitary heating structure, thereby preventing the undesirable escape of the necessary vapor, while vents are provided for the escape of surplus vapor.

50 The objects and features of the invention

will be readily understood by reference to the following detailed description accompanied by the illustrative drawings in which

Figure 1 is a perspective view of the invention in use with the heater in position surrounding a roll of hair to be treated; 55

Figure 2 is a plan view of the heater of the invention;

Figure 3 is an end view of the devices illustrated in Fig. 2; 60

Figure 4 is a side view of the same device and

Figure 5 is a section taken on the lines 5—5 of Fig. 4.

Referring now to the drawings, 10 indicates a pad for hair permanent waving which pad may be of any desired type and character.

Resting upon the pad and partly supported by a U-shaped member 11 is a spool or spindle 12 a portion of which is shown 65 in Fig. 1. As is clearly understood by those skilled in the art, the hair to be treated is customarily wound around such a spindle or spool. Since it is necessary to apply heat

to the hair wrapped around the spindle 12 70

the present invention provides a heater composed of a unitary structure 1 made up of inverted substantially U-shaped members 13

and 14, the member 14 having its lower edge 75 folded over and clamped to the member 13

as indicated at 15. By having the members 13 and 14 spaced apart as shown clearly in 80 Fig. 5 provision is made for the insertion

between these two members of an electrical heater element 16 of any desired character. 85

As shown in Fig. 1 the ends of member 14 are folded around and clamped to the member 13 in the same manner as the lower edge thereof, such clamping being illustrated

at 17. 90

In order that the heater may be held in position surrounding the roll of hair to be treated, provision is made whereby the same

may be detachably secured to the spindle 12. 95

Such an arrangement comprises clamping members 18 and 19 affixed to the respective ends of the unit by being secured to upstanding ears 20 by means of screws 21. Springs

22 are wrapped around the screws 21 in such 100 a manner as to apply tension to normally

hold the clamping members 18 and 19 in the position illustrated in Figs. 1, 3 and 5, that is, in position to permit their jaws 23 to extend around and under the spindle 12.

5 For permitting the removal of the unit from operative position relative to the spindle 12 handles 24 and 25 connect the respective members 18 and 19 as illustrated in the drawings. By pressing the handles 24 and 10 25 together the jaws 23 are extended permitting their removal from or engagement around the spindle 12. Since it is desirable that as little heat as possible be communicated to the scalp of the patient the entire arrangement for holding the heater in operative position, that is, the clamps 18 and 19 and the handles 24 and 25, is made of some good heat insulating material preferably bakelite. In addition to the heat insulating 20 qualities of such material a further advantage derived therefrom is the fact that such material weighs very little, thereby reducing the total weight of the entire assembly. In furtherance of this feature of reducing the 25 weight of the unit it is preferable that the members 13 and 14 which form the casing for the electrical heating element should be made of some light material which also is a good conductor of heat. It has been found in practice that aluminum serves this purpose very 30 well. The usual electrical conductors 26 for supplying energy to the element 16 are introduced into the space between the members 13 and 14 through an insulating block 27 35 resting upon and affixed to the top of the member 13 at approximately its mid-point. Inlets 28 are provided in the member 27 communicating with openings 29 in the top of member 13, thereby affording access to element 16.

It will be evident from the foregoing that due to the unitary structure of the heater that the major portion of the vapor, resulting from the application of heat to liquid 45 with which the roll of hair is impregnated, will be confined closely within the confines of the heater. The clamps by substantially closing the ends of the unitary heating structure aid in confining the vapor in close contact with the hair. It is necessary that some 50 of the vapor be permitted to escape. For this reason a pair of vents 30 are provided in the heater, such vents extending through the entire structure.

55 The improved structure is very easy to handle better results are obtained therefrom and it is inexpensive to manufacture.

I claim:

1. A device of the character described comprising a unitary heating member substantially U-shaped in cross section and jaw clamping members at each end of said heating member for contact with a hair engaging device.

65 2. A device of the character described com-

prising a unitary hollow shell substantially U-shaped in cross section of relatively light, heat conducting metal, a heating element therewithin, and jaw clamping members of heat-resisting material at each end of said shell for contact with a hair engaging device. 70

3. A device of the character described comprising a unitary heating member substantially U-shaped in cross section, and clamping members at each end of said heating members, said clamping members serving to close a portion of each end of said heating member. 75

4. A device of the character described comprising a unitary hollow shell substantially U-shaped in cross section of relatively light, heat conducting metal, a heating element therewithin, and clamping members of heat-resisting material at each end of said shell, said clamping members serving to close 80 a portion of each end of said shell. 85

5. A device of the character described comprising a unitary heating member substantially U-shaped in cross section, clamping members at each end of said heating member and handles connecting the said clamping members in pairs. 90

6. A device of the character described comprising a unitary heating member substantially U-shaped in cross section, clamping members at each end of said heating member and handles connecting the said clamping members in pairs, said clamping members and said handles being constructed of heat-resisting material. 95

In testimony whereof, I have signed my name to this specification.

HARRY BONAT.
